ACETYLENE GENERATOR

Filed March 29, 1938

UNITED STATES PATENT OFFICE

2,264,281

ACETYLENE GENERATOR

Maurice P. De Motte, Indianapolis, Ind., assignor
to Oxweld Acetylene Company, a corporation of
West Virginia

Application March 29, 1938, Serial No. 198,628

16 Claims. (Cl. 48—53.3)

This invention relates to acetylene generators of the carbide-to-water type, and particularly to relatively small portable generators capable of producing sufficient acetylene for field use.

Heretofore, portable generators of the carbide-to-water type have been constructed for field use, but they have been of such size that their cost is prohibitive for small jobs such as those encountered by the owners of small welding and repair shops. These relatively large portable generators often weigh in the neighborhood of two thousand pounds when fully charged, and as much as one thousand pounds when empty. They are large enough to readily accommodate control mechanism sufficient to impart to them operating characteristics of the highest standards. Other portable generators of relatively small size and light weight have been constructed including the carbide-to-water type, as well as those which operate on the water recession principle. While these relatively small generators accomplish to some extent the purpose for which they were designed, certain objections arise with their use including inadequate carbide-feed control mechanism; inaccessibility of parts for cleaning and repair; and complexity of design. The use of small water-recession type generators also may be objectionable because it is often impossible to prevent after-generation of acetylene during extended periods of generator idleness.

An object of this invention is to provide a relatively small-capacity light-weight inexpensive acetylene generator possessing operating characteristics equivalent to those of the relatively large portable generators.

Other objects include the provision of such a generator in which the carbide hopper is pivotally connected to the water tank by a connection capable of being adjusted to effect a substantially perfect seal between the two sections; the provision of such a generator including a pressure-responsive device for actuating the carbide feed valve and including manually operable means for closing the carbide feed valve independently of the action of such pressure-responsive device; the provision of such a generator including a pressure-responsive device of such construction that only a relatively slight movement of the diaphragm thereof is necessary to effect opening and closing of the carbide feed valve; the provision of such a generator having a pressure responsive device including a diaphragm capable of movement in response to relatively slight variations of acetylene pressure in the

generator, and mechanism located between the diaphragm and the carbide feed valve for amplifying the motion transmitted to the feed valve from the diaphragm; the provision of such a generator having a feed valve operating mechanism including a diaphragm connected to the feed valve by a magnifying linkage, and provided with a safety device adapted to prevent the flow of carbide past the feed valve in the event the magnifying linkage should break or become disconnected; the provision of such a generator including a unitary carbide feed control assembly; and the provision of such a generator including simple and effective interference mechanism which will insure the release of acetylene pressure therein before the generator can be opened.

Other objects and novel features of the invention will become apparent from the following specification considered in the light of the accompanying drawing, in which:

Fig. 1 is an elevational view, partly in section, of an acetylene generator to which the principles of this invention have been applied;

Fig. 2 is a sectional view taken along line 2—2 of Fig. 1; and

Fig. 3 is an enlarged sectional view taken along line 3—3 of Fig. 2.

The invention is shown in Fig. 1 as applied to 30 an acetylene generator of the carbide-to-water type, comprising an upper and a lower portion, the latter comprising a tank T having an opening at its upper end, adapted to contain water in its lower portion, and to confine acetylene thereabove. The upper portion of the generator comprises a carbide hopper H which is pivotally connected to the tank T by a hinge P (see Fig. 2). The hopper H is adapted to contain calcium carbide which is fed to the water within tank T 40 by a pressure-responsive device R. A manually operable feed-valve control mechanism M is associated with the pressure-responsive device R for initially opening the feed valve, and for finally closing the same when generation of acetylene is to be terminated.

The tank T comprises a substantially cylindrical shell 10 closed at its bottom by a base 12, and provided with a shoulder plate 14 at its upper extremity. The tank T is provided with a water overflow plug 18, and a residue valve 20. It is further provided with a sludge-agitating paddle 22 mounted on a shaft 24, the latter being journaled in diametrically opposed bearings 26 and 28. The bearing 28 is in the form of a packing gland for accommodating one end

of shaft 24 which extends to a point outside of the shell 10. That portion of shaft 24 which extends outside of the shell 10 is bent to form a handle 30. Thus it is seen that oscillating the handle 30 causes stirring of the sludge within the bottom of the shell 10 by the corresponding movement of the paddle 22. The handle 30 is maintained in vertical position when not in use by a pivotally mounted yoke 32.

In order to prevent the splashing of water within the shell 10 when the generator is moved over rough terrain in field use, a baffle 34 is fixed therein. It comprises a pair of angle plates, the outer edges of which are welded to the inner surface of the shell 10, and the abutting apices of which may or may not be welded together.

The hopper H comprises a sheet metal body portion 36 having an inverted frusto-conical lower portion 38 adapted to be attached to a forged or cast hopper outlet 40. The outlet 40 is adapted to cooperate with a member 42 welded or otherwise fastened to the shoulder plate 14 of the shell 10. The member 42 is provided with a pair of spaced lugs 44 (see Fig. 3) adapted to receive a bearing portion 46 of the outlet 40. In order to provide means for insuring accurate parallel alignment of the cooperating surfaces of outlet 40 and member 42, an adjustment is provided between the bearing 46 and a pivot pin 48 passing through the lugs 44. The adjustment may comprise an eccentric bushing 50 mounted between the pin 48 and the bearing 46. A set screw 54, threaded into bearing 46, is adapted to lock the bushing 50 and bearing 46 relative to each other in any one of a plurality of adjusted positions. The one end of bushing 50 is provided with a plurality of circumferentially spaced apertures 56 adapted to receive a pin for effecting rotative movement of the bushing 50. A portion of the bearing 46 is machined out to afford access to at least one of the openings 56.

In order to avoid undue straining of the hinge P when the hopper H is opened, an abutting element is connected to the hopper. Referring to Fig. 2, this element comprises a strap 57 welded to the hopper at the top of the frusto-conical portion 38, and to the bearing 46. It is provided with a portion 59 adapted to rest on the shoulder plate 14 and support the hopper H when the latter is in an open position.

A rubber gasket 58 is adapted to be positioned between the outlet 40 and the member 42 for insuring an hermetical seal between the hopper H and the tank T. The hopper H is held in sealed relation with respect to the tank T by a releasable connection including a threaded rod 60 pivotally mounted on the member 42 by a pin 63. A handwheel 62 is threaded on the rod 60 and is adapted to cooperate with a yoke 64 formed integral with the element 40. The handwheel 62 is attached to the rod 60 in a manner to prevent its complete removal therefrom, but is capable of being loosened sufficiently to permit it to clear the yoke 64.

The carbide hopper H is further provided with a charging door 66 having an observation window 68 located therein. An additional window 69 is provided in said hopper at a point diametrically opposite from the window 68, to admit light thereinto for visually determining the quantity of carbide within the hopper.

A valve 72 is adapted to close the opening between the hopper H and the tank T. It comprises a seating element removably fastened to a valve rod 74 by a nut 76. The valve rod 74 extends

vertically upward and in alignment with the opening between the hopper H and tank T. Its upper portion is connected to the pressure-responsive device R and to the valve-closing mechanism M.

The pressure-responsive device R is adapted to control the operation of the valve 72 in response to variations in pressure of acetylene within the upper portion of tank T. It comprises an assembly which may be mounted in or removed from the hopper H as a unit for purposes of inspection, cleaning and repair. Referring again to Fig. 1, the pressure-responsive device R includes a resilient diaphragm 76 covering an opening in the upper portion of the hopper H, and in vertical alignment with the opening between the hopper H and the tank T. For the purpose of limiting the size of the respective parts of the generator so as to maintain a minimum weight, the diaphragm is so constructed that movement is imparted to it by even relatively slight variations in acetylene pressure within the tank T. The pressure within hopper H corresponds to the pressure within tank T due to the vent 142 leading from within outlet 40 to the interior of hopper H (see Fig. 2). In order to transmit sufficient movement to the valve rod 74 to effect proper opening of the valve 72, a magnifying linkage has been employed between the diaphragm 76 and the valve rod 74. As shown in Fig. 1, this linkage comprises a member 78 integral with a flange ring 80 which surrounds the periphery of the diaphragm 76 and contacts its lower surface. The member 78 is pivotally connected with one end of a cross link 82, the opposite end of which is pivotally connected with one end of a link 84. The opposite end of link 84 is connected to a link 86. The two ends of link 86 are pivotally attached to a member 88 integral with the flange ring 80, and the valve rod 74, respectively. The center of the diaphragm 76 is attached to one end of a link 90, the opposite end of which is pivotally connected to the cross link 82. The points of attachment of the links 84 and 90 to the respective cross links 86 and 82 may be such as to provide any convenient amplification of the movement of diaphragm 76. However, in the present embodiment they are so connected to provide a six to one ratio of movement between the diaphragm and the rod 74. Thus it is seen that slight movement of the diaphragm 76 will be amplified by the linkage between it and the rod 74 so as to substantially increase the latter's movement when movement of the former occurs. The above-described magnifying linkage, and a substantial portion of the valve rod 74 is enclosed within a housing 73, thus preventing the carbide within hopper H from interfering with the operation of said linkage and rod.

In order to prevent feeding of carbide from the hopper H to the tank T in the event the magnifying linkage breaks, or becomes disconnected, a safety valve 75 (see Fig. 2) is provided on the rod 74 above the valve 72 so that it will seal the opening between the hopper H and tank T in the event rod 74 drops to an open position due to such breakage or disconnection.

The top or atmospheric side of the diaphragm 76 supports a pressure plate 92 rigidly fixed thereto by the connection between link 90 and diaphragm 76. A compression spring 94 is supported on its one end by the plate 92 within a housing 96 which is vented to the atmosphere. The spring 94 is adapted to be compressed to different de-

grees for the purpose of varying the pressure on the atmospheric side of the diaphragm 76 in order to vary the effectiveness of said diaphragm. This spring adjustment may be accomplished by providing an adjusting plate 98 in position within housing 96 to abut against the end of spring 94 opposite to the end in contact with plate 92. The plate 98 is threaded onto a hollow screw 100 located within the coils of spring 94 and extending through, and journaled in, a bushing 102 welded to the top of housing 96. The screw 100 is provided with an end portion 104 adapted to form a thrust bearing with the upper end of the bushing 102. A guide rod 106 is fixed to the head of housing 96, depending therein and passing through an aperture within the plate 98 for effecting axial movement of plate 98 when screw 100 is rotated.

A handle 108 is provided with a cam portion 110 adapted to fit within a slot 105 in the top of bearing 104 so that rotation of the handle 108 in a horizontal plane will effect rotation of the screw 100 to thereby cause axial movement of the plate 98 and thereby vary the compression of spring 94.

The manual valve-closing mechanism M includes a rod 112 extending through the hollow screw 100. Its one end is connected to the handle 108 by a pin 114, and its other end is provided with a collar 116 adapted to support a disc 118. The disc 118 is adapted to provide a releasable connection between the rod 112 and the diaphragm 76 to effect movement of the diaphragm only in one direction. This may be accomplished by providing a cylindrical shell 120 open at both ends, and welded at its lower end to the plate 92. The upper end of the shell 120 may be provided with an inturned edge adapted to overlie the disc 118. Vertical upward movement of the rod 112 may be effected by the downward movement of the handle 108 in a vertical plane so that the cam surface 111 of the cam portion 110 engages the bottom of the slot in the bearing 104. A compression spring 124 surrounds the rod 112 and abuts against the lower end of the hollow screw 100 and the upper surface of the disc 118.

Thus it is seen that when the handle 108 is in the position shown in Fig. 1, the cam surface 111 acts against the bottom of the slot 105 to effect vertically upward movement of the rod 112, thus lifting the diaphragm 76 and the valve rod 74 to effect positive closing of the valve 72. Rotation of the handle 108 in the same vertical plane, through 180 degrees, will permit vertical downward movement of the rod 112 so that the disc 118 is moved out of engagement with the inturned edge of the shell 120. This will permit the spring 94 to effect a downward movement of the diaphragm 76, and a corresponding downward movement of valve rod 74. The spring 124 functions to maintain the rod 112 in fixed position and prevents it from vibrating when the rod 112 is moved to a position out of engagement with the shell 120.

The tank T is provided with a safety-relief valve 126 connected to the gas-collecting portion of said tank. Acetylene gas generated within the tank T passes therefrom through a pipe 128 to a hydraulic back-pressure valve 130. The gas exits from the hydraulic back-pressure valve 130 through a nipple 132 to a service outlet 134. An additional safety-relief valve 136 is connected to the service outlet and the back-pressure valve 130.

In order to insure the release of acetylene under

pressure within the tank T and the hydraulic back-pressure valve 130 before the generator can be opened, an interference mechanism has been provided. Referring to Fig. 1, the interference mechanism comprises a horizontally reciprocable rod 138 having portions adapted to interfere with the rotation of handwheel 62 and the pivoting of rod 60 when it is in the position shown in solid lines, and to release these elements when moved leftward to the position shown in dot and dash lines. The one end of rod 138 is connected to the operating lever 129 of the relief valve 126. It extends angularly downwardly from lever 129 to a point slightly above the shoulder plate 14, thence substantially horizontally through a guide 131. Just beyond the guide 131, rod 138 is right-angularly bent, forming a portion which passes through a slot in the extended end 133 of the pivot pin 63. The rod 138 then extends angularly upwardly and is connected to the operating lever of relief valve 136, which lever is located behind said relief valve and is, therefore, not shown in the drawing.

A member 135, welded to rod 138, is provided with a portion 137 adapted to engage within slots 139 in the handwheel 62 when the rod 138 is in its right-hand position. In this position portion 137 prevents the unscrewing of handwheel 62, and thereby serves as an additional precaution against opening the generator before releasing the gas pressure therein.

Horizontal reciprocation of the interference rod 138 is effected by turning, or oscillating, a hand lever 127 connected to lever 129. Inasmuch as the interference mechanism is actuated only when it is desired to open the generator, it is constructed and arranged in a manner to avoid its accidental operation. The valve 126 is adjusted so that it will be closed when handle 127 is directed inwardly toward the hopper H. Thus handle 127 is protected from accidental manipulation by virtue of its inaccessible location. Furthermore, this handle must be rotated in a counter-clockwise direction in order to effect the necessary horizontal movement of rod 138 to permit opening of the generator. The angular adjustment of lever 129, for closed position, and the counter-clockwise motion necessary to effect its opening, provides a dead center position beyond which lever 129 must pass before the opening or closing of the valve 126 can be effected. Thus it is seen that with the lever 129, handle 127, and rod 138 in the position shown in solid lines in Fig. 1, relief-valves 126 and 136 are closed; handwheel 62 cannot be rotated; nor can rod 60 be turned about its pivot. Counter-clockwise movement of handle 127 from its position in solid lines to its position in dot and dash lines will effect the movement of rod 138 to the left, thus opening valves 126 and 136, and releasing handwheel 62 as well as pivot pin 63.

Assuming that the tank T is filled with water to the overflow plug 18, the hydraulic back-pressure valve 130 is filled with water, the carbide hopper H is charged with calcium carbide, and the handle 108 is in the position shown in Fig. 1, the operation of the generator is as follows.

Moving the handle 108 in a vertical plane through 180 degrees will release the diaphragm 76. The action of the spring 94 will then depress diaphragm 76, and the latter's movement will be amplified by, and transmitted to the valve rod 74, by the linkage including the levers 78 and 86. Thus valve 72 will be opened to cause calcium carbide to flow from the hopper H into the water

within tank T. As the generated gas increases in pressure within the tank T, it will force the diaphragm 76 upwardly against the action of spring 94 to thereby close the valve 72, thus shutting off the flow of carbide to the water within tank T.

As the pressure decreases in the tank T due to the withdrawal of acetylene therefrom through the service outlet 134, the reduced pressure will be transmitted to the diaphragm through the vent 142 between the hopper H and the tank T. When the pressure within tank T and hopper H decreases to a point below the pressure exerted by the atmosphere and the spring 94, diaphragm 76 will be moved to open the valve 72 thereby continuing the feed of carbide to the water within tank T.

When it is desired to shut down the operation of the generator over an extended period, it is only necessary to rotate the handle 108 in a vertical plane through 180 degrees to the position shown in Fig. 1.

When it is desired to recharge the generator, or inspect it, the rod 138 is moved to the left by turning handle 127 in a counter-clockwise direction, thus releasing the pressure within tank T and the hydraulic back-pressure valve 130. This leftward movement of rod 138 also releases handwheel 62 and pivot pin 63. The handwheel 62 is then loosened and the rod 60 is pivoted about its pivot pin 63 thereby releasing the hopper H and permitting it to be rotated about the hinge P.

Although the various features of the improved generator have been shown and described in detail to fully disclose one embodiment of this invention, it will be evident that numerous details, and certain features, may be used without others, without departing from the principles of the invention.

I claim:

1. An acetylene generator comprising a lower portion adapted to contain water; an upper portion having a hopper adapted to contain calcium carbide and provided with a carbide feed opening; a carbide feed valve adapted to control the flow of carbide from said upper portion through said opening to the water within said lower portion; a pressure-responsive device connected to said feed valve and having a diaphragm constructed for movement in response to relatively slight variations of acetylene pressure in said generator; and means connecting said diaphragm and said valve and adapted to transmit the movement of said diaphragm to said valve, said means comprising a pair of inter-connected overlapping links adapted to amplify the movement transmitted to said valve from said diaphragm; said diaphragm, valve, and carbide feed opening being arranged in substantially axial alignment.

2. An acetylene generator as claimed in claim 1, in which such connecting means is wholly enclosed within said calcium carbide hopper.

3. An acetylene generator as claimed in claim 1, in which such connecting means comprises a pair of pivotally mounted links, and in which said diaphragm is connected at a point intermediate the ends of one of said links, said valve is connected to one end of the other link, and one end of the former link is connected at a point intermediate the ends of the latter link.

4. An acetylene generator as claimed in claim 1, in which said carbide feed valve is provided with safety means which comprises a valve located above said carbide feed valve and in alignment therewith.

5. An acetylene generator as claimed in claim 1,

in which said links are located entirely within the upper portion of said generator and separated from the carbide therein by a housing.

6. An acetylene generator comprising a lower portion adapted to contain water and having an opening at its upper end; an upper portion adapted to contain calcium carbide and having an opening in its lower end; a carbide feed valve adapted to control the flow of carbide from said upper portion through said openings into the water within said lower portion; a pressure-responsive device connected to said feed valve including a diaphragm having one surface exposed to the pressure of the generated acetylene and constructed for movement in response to relatively slight variations of acetylene pressure within said generator; a compression spring acting on the other side of said diaphragm; spring-adjusting means for varying the pressure exerted by said spring; manually operable means for controlling said spring-adjusting means; and auxiliary means independent of said spring-adjusting means but associated with said manually operable means for closing said carbide feed valve independently of the action of said spring.

7. An acetylene generator as claimed in claim 6, in which said auxiliary means comprises a rod extending through said spring-adjusting means and connected to said diaphragm.

8. An acetylene generator as claimed in claim 6, in which said auxiliary means comprises a rod extending through said spring-adjusting means and provided with a releasable connection to said diaphragm, whereby said rod is adapted to move said diaphragm only in the direction which will close said carbide feed valve; and a spring for maintaining said rod in fixed position when it is released from said diaphragm.

9. An acetylene generator as claimed in claim 6, in which said auxiliary means comprises a rod extending through said spring-adjusting means and connected to said manually operable means, and in which said manually operable means is provided with a cam surface adapted to engage a slotted member connected to said spring-adjusting means, whereby rotation of said manually operable means in a horizontal plane will effect adjustment of said spring, and movement of said manually operable means in a vertical plane will effect closing of said carbide feed valve independently of said spring-adjusting means.

10. An acetylene generator comprising a lower portion adapted to contain water and provided with an opening at its upper end; an upper portion adapted to contain calcium carbide and provided with a carbide feed opening at its lower end; a carbide feed valve adapted to control the flow of carbide from said upper portion through said carbide feed opening to the water within said lower portion; a pressure-responsive device connected to said feed valve and having a diaphragm constructed for movement in response to relatively slight variations of acetylene pressure in said generator; means connecting said diaphragm and said valve and adapted to amplify the movement of said diaphragm and transmit said amplified movement to said valve; a spring acting against one side of said diaphragm; spring-adjusting means for varying the effectiveness of said diaphragm; manually operable means connected to said diaphragm and adapted to close said feed valve independently of the action of said spring; a housing enclosing said spring, said spring-adjusting means, and said manually operable means; the construction and arrange-

ment of the parts being such that the amplifying means, diaphragm, spring, spring-adjusting means, manually operable means, and housing may be removed from said generator as a unitary assembly.

11. A unitary assembly for use with an acetylene generator comprising a housing; a diaphragm closing one end of said housing; a spring and a spring-adjusting means located within said housing, said spring acting against said diaphragm; said spring-adjusting means including a plate acting against said spring, and means for moving said plate to vary the pressure which said spring exerts against said diaphragm; manually operable means for operating said spring-adjusting means; and means connected to said manually operable means and provided with a releasable connection to said diaphragm, whereby said diaphragm may be moved against the pressure exerted thereon by said spring.

12. An acetylene generator comprising a lower portion adapted to contain water; an upper portion pivotally connected to said lower portion and adapted to contain calcium carbide, said portions being provided with sealing means including a pivotally mounted element and a clamping means therefor, said element and clamping means being adapted to be locked in position to effect a gas-tight seal between said portions; a hydraulic back-pressure valve mounted on said lower portion; pressure-relief valves connected to said lower portion and said hydraulic valve; and means for simultaneously opening said relief valves and for releasing said element and said clamping means.

13. An acetylene generator as claimed in claim 12, in which said clamping means comprises a handwheel screwed onto said pivotally mounted element, and in which such opening and releasing means comprises a reciprocable rod having portions adapted to engage slots in the extended end of the pivot pin of said element and in said handwheel.

14. An acetylene generator comprising, in combination, a tank adapted to contain a body of water; a hopper adapted to contain calcium carbide and having an outlet communicating with said tank for feeding such carbide into such water; mechanism for controlling such feeding of carbide, comprising a valve adapted to open and close said outlet, a flexible diaphragm constituting a part of the top wall of said hopper and having one side thereof subject to the pressure of acety-

- lene within said tank, and the other side subject to the pressure of a spring, means for adjusting said spring to vary the pressure exerted thereby on said diaphragm, means within said hopper for connecting said valve to the central portion of said diaphragm, such connecting means being constructed and adapted to amplify even the smallest motion of such central portion of the diaphragm while transmitting such amplified motion to said valve, and a manually-operable device outside said hopper and swingable into either of two positions, means between said device and said diaphragm constructed and arranged so that the swinging of said device to one of said positions moves said central portion of the diaphragm in one direction to close said valve and to retain the same in closed position independently of the pressure exerted on said diaphragm by said spring, and so that the swinging of said device to the other of said positions releases said diaphragm and said valve to automatically feed carbide into said tank in response to variations of acetylene pressure against said diaphragm; a housing enclosing said spring and secured to said hopper; and a housing inside said hopper and vertically coaxial with said spring housing, said inside housing enclosing said means which amplifies and transmits motion from said diaphragm to said valve.
15. An acetylene generator comprising a tank adapted to contain water; a calcium carbide hopper hinged to said tank and adapted to form an hermetical seal therewith; means for clamping said hopper and tank in sealed relation; automatic pressure-relief means for relieving excessive pressure within said generator, said relief means also being manually operable for relieving the operating pressure within said generator; and interference mechanism connected to said pressure-relief means and adapted to cooperate with said clamping means to lock the latter, the construction and arrangement being such that manual operation of said relief means must be effected before such clamping means can be released.
16. An acetylene generator as claimed in claim 15, in which an operating lever is connected to said relief means and to said interference mechanism and adapted to be swung past a dead center position in order to operate said relief means and release said clamping means.

MAURICE P. DE MOTTE.
